UNITED STATES PATENT OFFICE.

JAMES MOORE, OF HANOVER, ILLINOIS.

CHURN.

SPECIFICATION forming part of Letters Patent No. 740,297, dated September 29, 1903.

Application filed April 27, 1903. Serial No. 154,557. (No model.)

To all whom it may concern:

Be it known that I, JAMES MOORE, a citizen of the United States, residing at Hanover, in the county of Jo Daviess and State of Illinois, have invented certain new and useful Improvements in Churns, of which the following is a specification.

My invention relates to improvements in churns, and refers particularly to a novel form of dasher designed for use in a rotary-body churn.

One object of my invention is the provision of a churn in which the dasher can be easily adjusted to fit the body or receptacle of the churn, which will remain in position, and which can be easily applied and removed.

Another object of my invention is the provision of a dasher which can be made in various forms, as circumstances require, which will be thoroughly efficient in operation, and which can be produced at a very low price.

To attain these objects my invention consists of a churn-dasher embodying novel features of construction and combinations of parts, as substantially disclosed herein.

Figure 1 represents a side view of a churn, partly broken away to show my dasher in position therein. Fig. 2 represents a perspective view of my dasher detached. Fig. 3 represents a side view of a modified form of my dasher, and Fig. 4 represents a detail view of the adjusting device for holding the sections of the dasher.

In the drawings, A designates the frame or support of my churn, having bearings B to receive the journal C on the body or receptacle D, which is provided with a crank E for rotating said body. The body is provided with a mouth or opening F, forming a rim G, and fitting in the opening is the cover H.

My novel dasher consists of the two sections, each composed of the parallel bars J, connected by rungs J', upon which are mount-

ed the revolving paddles or agitators J², and the sections are hinged together by means of 45 the screw or clamping device K, which comprises the screw-cap K, having the binding-screw K' and the clamping-nut K², which is engaged by the screw-cap, and this device firmly holds the sections in any desired ad- 50 justment according to the shape and size of the churn. In the form of my dasher shown in Fig. 3 I provide, in addition to the bars J, the auxiliary bars L, which carry a series of rotating paddles or agitators M.

From the foregoing description, taken in connection with the drawings, the operation of my churn will be readily understood, and it is evident that the body is revolved by means of the crank and that the wheels or 60 agitators rapidly revolve and effect a quick churning of the cream and produce the butter in a rapid manner without fatiguing the operator.

I claim—

1. A churn-support consisting of the frame, the body mounted in the frame, the crank for revolving the body, the dasher arranged in the body and composed of a series of hinged sections, revolving paddles or agitators 70 mounted in said sections, and a clamping device for securing the sections in any desired adjustment.

2. A churn-dasher composed of two hinged sections, the revolving paddles or agitators 75 mounted in said sections and the clamping device for securing the sections in any desired adjustment.

In testimony whereof I affix my signature in presence of witnesses.

JAMES MOORE.
